[57] CLAIM

The ornamental design for a bottle and cap or similar article, substantially as shown and described.

DESCRIPTION

FIG. 1 is a top plan view of a bottle and cap showing my new design;

FIG. 2 is a front elevational view thereof, the back being identical to the front;

FIG. 3 is a bottom view thereof;

FIG. 4 is a right side elevational view thereof, the left side being identical to the right side.

The beveled edges are plane surfaces.
